(57) **CLAIM**

The ornamental design for a water pump adapter, as shown and described.

DESCRIPTION

FIG. 1 is a perspective view of one embodiment of the water pump adapter of the present invention;
FIG. 2 is a right side, end view of the embodiment shown in FIG. 1;
FIG. 3 is a left side, end view of the embodiment shown in FIG. 1;
FIG. 4 is a front view of the embodiment shown in FIG. 1;
FIG. 5 is a view of one side of the embodiment shown in FIG. 1;
FIG. 6 is a rear view of the embodiment shown in FIG. 1; and,
FIG. 7 is a view of the other side of the embodiment shown in FIG. 1.
